UNITED STATES PATENT OFFICE

CARROLL BURTON, OF JOHNSTOWN, PENNSYLVANIA

CAR COUPLER

Application filed February 12, 1929. Serial No. 339,419.

This invention relates to car couplers and more particularly to car couplers for mine cars and the like, and has for one of its objects the provision of a coupler of this class which will be sufficiently flexible to operate 5 regardless of the irregularities and sharp curves of mine tracks.

In the drawings:

Figure 1 is a sectional elevation of adjacent ends of two cars having the coupler mechanism of this invention applied thereto.

Figure 2 is an enlarged fragmentary sectional elevation through the center line of the coupling.

Figure 3 is an enlarged plan view thereof.

Figure 4 is a sectional view taken on the line IV—IV of Figure 1.

Referring more particularly to the drawings, the numeral 2 designates the car having the coupler-head thereon, and the numeral 3 designates the car having the coupler loop or bail thereon.

The coupler-head comprises a hollow receiving body portion 4 and a shank portion 5. The body has a web 4^a intermediate its ends, and has its side walls cut away, as at 4^b, forward of the web 4^a so as to form a clevice-like receiving head adapted to receive the bail or loop carried by the car 3.

A transverse coupler-head supporting member 6 formed from a pair of channel sections arranged back-to-back and securely riveted in position is provided for supporting the coupler-head. The member 6 is provided 35 with an opening 7 therethrough through which the shank 5 of the coupler-head projects. The opening 7 is of a sufficient diameter to provide clearance for a slight rocking movement of the coupler-head.

A load-receiving strap or draw-bar 8 is provided along the bottom of the car above the transverse member 6 and is secured to said member, a second load-receiving strap or draw-bar 9 being mounted under the member 6 and secured thereto. The straps 8 and 9 extend under the car and are secured to the main frame 9^a of the car so as to deliver the pulling loads directly to the car frame. A yoke member 10 is around the forward ends 50 of the traps 8 and 9 and has its side portions

extending parallel and with slight clearance only along the side faces of the coupler-head 4, so as to serve as guides to prevent side swinging movement of the coupler-head, while the straps 8 and 9 are spaced a sufficient distance above and below the coupler-head to permit a limited vertical movement of the coupler-head when the cars are moved over a mine track which is irregular in a vertical direction due to the irregular mine floors.

If it is desired to provide for rotary dumping of the cars the rear end of the body portion 4 of the coupler head may be made cylindrical so as to permit the coupler head to rotate within the confines of the yoke member 10, thereby permitting the cars to be dumped on a rotary dump without uncoupling.

The coupler-head is adapted to be normally flexible and held in a horizontal position by equal strength coiled springs 12 and 14 mounted around the coupler-head shank 5 on opposite sides of the member 6. Suitable follower rings 15 and 16 are mounted on the shank 5 and bear against the ends of the springs 12 and 14 opposite the member 6. A nut 17 is threaded on the free or rear end of the shank and serves to adjust the tension of the springs 12 and 14 so as to apply sufficient tension to the springs to maintain the coupler-head normally in horizontal position. The nut 17 is adapted to be locked in its adjusted position by a cotter-pin 18.

Suitable stop-sleeves 19 and 20 are mounted on the shank 5 on the opposite sides of the supporting member 6 and have a combined length materially less than the length of the shank between the follower rings 15 and 16. The springs 12 and 14 are of equal strength and serve to center the coupler-head shank 5 in the support 6 and, therefore, the sleeves 19 and 20 will be spaced a substantially equal distance from the member 6 and permit a limited horizontal movement of the coupler-head relative to the support 6.

The body or head portion 4 of the coupler-head is provided with a pawl 22 pivotally mounted for vertical movement on a pin 23. The top wall of the head 4 is slotted, as at 100

24, to permit the pawl 22 to swing upwardly to receive or release the coupler loop or bail carried by the car 3. The lower wall of the coupler-head 4 is recessed, as at 25, 5 to receive the end of the pawl 22 and lock it in position. A ring 26 is provided in the upper portion of the pawl 22 by which an operator may pull up the pawl to release the coupler loop or bail.

10 The coupler loop or bail on the car 3 is designated by the numeral 27 and is rigidly secured on a spacer-block 28 by bolts 29. The spacer-block 28 is secured to upper and lower straps or draw-bars 30 by bolts 31, 15 which straps extend rearwardly and are secured to the main frame 32 of the car by bolts 33, so as to deliver the pulling strains from the bail 27 directly to the main frame 32 of the car. The bail or loop 27 is of a 20 materially greater width than the coupling head and the forward or closed end of the loop is widened materially, as at 27^a, so as to provide for the side swings made by mine cars. The radius of the curves in mine tracks 25 is about one-third of that in ordinary railroad tracks, consequently a wide swing must be allowed for.

The present coupler mechanism is particularly adapted for use on mine and similar 30 cars, and is designed so as to overcome the many problems peculiar to this class of use.

While I have shown and described one specific embodiment of my invention, it will be understood that I do not wish to be limited 35 thereto, since various modifications may be made without departing from the scope of my invention as defined in the appended claims.

I claim:

40 1. In combination with a mine car, a transverse coupler-head supporting member, a load receiving draw-bar strap mounted along the bottom of said car above said transverse member and secured to said transverse member, a second draw-bar strap mounted along the bottom of said car under said transverse member and secured to said transverse member, means for securing said draw-bar straps together and to the main 45 frame of said car, said transverse member being provided with an opening to receive the shank of a coupler-head, a coupler-head comprising a receiving body portion and a shank, said shank portion extending freely 50 through said opening in said transverse member, and resilient means for pressing said coupler-head in opposite directions relative to said transverse member and adapted to normally maintain said head in substantially 55 central position with freedom to rock up and down and to yield in the direction of load, a yoke member mounted around the forward ends of said draw-bar straps, said yoke member having its side portions extending parallel with slight clearance along the faces of

5 said body portion of the coupler-head so as to guide said head and prevent side swinging thereof, and said draw-bar straps being spaced vertically above and below said coupler-head a sufficient distance to permit a 70 limited vertical movement of said coupler-head caused by the irregularities of the track.

2. In combination with a mine car, a transverse coupler-head supporting member, means including a draw-bar strap mounted along the bottom of said car and secured to said transverse member and to the main frame of said car for transmitting loads from said transverse member to the main frame of said car, said transverse member being 75 provided with an opening to receive the shank of a coupler-head, a coupler-head comprising a body portion and a shank, said shank portion extending freely through said opening in said transverse member, and resilient means for pressing said coupler-head in opposite directions relative to said transverse member and adapted to normally maintain said head in substantially central position with freedom to rock up and down and to yield in the direction of load, a yoke member secured to the forward end of said draw-bar strap, said yoke member having its side portions extending parallel with slight clearance along the faces of said body portion of 80 the coupler-head so as to guide said head and prevent side swinging thereof, and said yoke being spaced vertically above and below said coupler-head a sufficient distance to permit a limited vertical movement of said coupler-head caused by the irregularities of the track.

3. In combination with a mine car, a transverse coupler-head supporting member, means including a draw-bar strap mounted along the bottom of said car and secured to said transverse member and to the main frame of said car for transmitting loads from said transverse member to the main frame of said car, said transverse member being 85 provided with an opening to receive the shank of a coupler-head, a coupler-head comprising a body portion and a shank, said shank portion extending freely through said opening in said transverse member, and resilient means for pressing said coupler-head in opposite directions relative to said transverse member and adapted to normally maintain said head in substantially central position with freedom to rock up and down and to yield in the direction of load, a yoke member secured to the forward end of said draw-bar strap, said yoke member having its side portions extending parallel with slight clearance along the faces of said body portion of 90 the coupler-head so as to guide said head and prevent side swinging thereof, and said yoke being spaced vertically above and below said coupler-head a sufficient distance to permit a limited vertical movement of said coupler-head caused by the irregularities of the track.

In testimony whereof, I have hereunto set my hand.

CARROLL BURTON.
